(57) **CLAIM**

The ornamental design for an element holder, as shown and described.

DESCRIPTION

FIG. 1 is a front perspective view of an element holder showing our new design;

FIG. 2 is a front perspective view thereof;

FIG. 3 is a back perspective view thereof;

FIG. 4 is a front elevational view thereof;

FIG. 5 is a side elevational view thereof;

FIG. 6 is a top plan view thereof; and,

FIG. 7 is a bottom plan view thereof.

The broken lines define the bounds of the claimed design in the present application, and form no part thereof.
